FURNITURE CONSTRUCTION

Olley C. Lauber, Archbold, Ohio, assignor to Lauber Manufacturing Company, Archbold, Ohio, a corporation of Ohio

Filed Dec. 28, 1962, Ser. No. 247,929

10 Claims. (Cl. 108—156)

This invention relates to improved furniture construction and more particularly to an improvement in the attachment of a leg to a table, chair, or other article of furniture.

Even though a number of methods and means are known in the art of furniture construction for attaching legs to tables, chairs, or the like the present invention provides improved means for effecting such an attachment. The attachment according to the invention requires less material and fewer operations than heretofore necessary and further enables the legs to be assembled or disassembled easily so that the article of furniture can be readily knocked down for shipment to substantially lower shipping costs.

It is, therefore, a principal object of the invention to provide an improved leg construction for furniture which is more simple, less expensive, and enables the legs to be more easily assembled and disassembled than heretofore.

Numerous other objects and advantages of the invention will be specifically discussed below and still others will be apparent from the following discussion, reference being made to the accompanying drawings, in which:

FIG. 1 is a fragmentary view in perspective of an article of furniture embodying a leg construction according to the invention;

FIG. 2 is a fragmentary view in cross section taken along the line 2—2 of FIG. 1;

FIG. 3 is a view in perspective similar to FIG. 1, but with the leg removed;

FIG. 4 is a view in perspective of the leg of FIG. 1, but looking down at the leg;

FIG. 5 is a view in perspective similar to FIG. 1 of a slightly modified construction; and

FIG. 6 is a fragmentary view in cross section taken along the line 6—6 of FIG. 5.

Referring to the drawings, and more particularly to FIGS. 1 and 2, an article of furniture is a table, in this instance, although it could equally well be a chair or other article of furniture for which the leg attachment according to the invention is applicable. The article includes a supporting member or table top 12 from which aprons 14 and 16 and a leg 18 depend. The supporting member 12 can be of any suitable thickness which will depend, in part, on its ultimate use, for example, whether it is a table top or a seat, and also upon the overall size. The top 12 preferably has a lower flat surface 20, at least in the area adjacent the aprons 14 and 16 and the end of the leg 18.

Referring more particularly to FIGS. 2 and 3, the supporting member 12 has shallow grooves 22 and 24 routed or otherwise suitably formed therein to receive upper edges of the aprons 14 and 16. The grooves 22 and 24 preferably terminate in spaced relationship near the corners, as shown in FIG. 3, before they would otherwise intersect. The ends of the grooves 22 and 24 thereby help to position the aprons 14 and 16 longitudinally and determine the minimum spacing between them, where such spacing is desired. The aprons 14 and 16 are glued in the respective grooves 22 and 24 but not over their entire lengths. Rather, the adhesive is spread only over approximately the middle two-thirds of the lengths of the aprons, depending upon their size, but in any case with several inches at each end of the aprons being left unattached for purposes of expansion. This enables the

2

aprongs 14 and 16 to expand relative to the supporting member 12 without any undue stresses being set up.

As shown in FIG. 3, adjacent ends 26 and 28 of the aprons 14 and 16 are preferably spaced apart somewhat for purposes of expansion, although the spacing is not otherwise necessary. For purposes of the invention, the aprons 14 and 16 can even be joined at their ends if expansion is not a problem.

While the aprons 14 and 16 are shown as extending perpendicularly from the surface 20, they can also converge or slope away from the edges of the supporting member 12, in which instance the ends 26 and 28 can be cut back accordingly so that they will not interfere with one another. Oppositely, the aprons 14 and 16 can diverge or extend toward the edges of the supporting member 12, with the ends 26 and 28 extended further, if the aprons diverge sufficiently, so that the gap between them will not be excessive. It will be noted that as long as the ends of the aprons 14 and 16 are generally planar, the "apron angle," meaning the angle formed between sidewalls of the aprons 14 and 16 in any plane parallel to the surface 20, will always be the same, even if the aprons converge or diverge. It may be noted that the construction can also be used with tables having circular or oval tops and aprons, in which case the apron angle is substantially 180°.

Referring more particularly to FIG. 4, the leg 18 in this instance is generally square with two outer flat surfaces 30 and 32 which are fully exposed beyond the aprons 14 and 16, and two inner flat surfaces 34 and 36. Two elongated leg grooves 38 and 40 extend from a butt end 42 of the leg 18 downwardly into the leg and open upon the surfaces 34 and 36 to receive the aprons 14 and 16. The grooves 38 and 40 have bottom walls or edges 44 and 46 which are spaced apart by a distance not exceeding the spacing between the ends 26 and 28 of the aprons 14 and 16. The bottom walls 44 and 46 of the grooves 38 and 40 then cannot interfere with the ends 26 and 28 when the leg 18 is assembled with the aprons 14 and 16, with the aprons 14 and 16 inserted in the grooves 38 and 40, as shown in FIGS. 1 and 2. If the apron ends are closer together than the bottoms of the grooves, the leg cannot be assembled and the table probably will be returned to the manufacturer as defective. To prevent this possibility, the grooves 22 and 24 can terminate short of one another, as previously discussed, to determine the minimum spacing between the apron ends 26 and 28.

The bottom edges 44 and 46 of the grooves 38 and 40 need not be parallel, as long as they clear the ends 26 and 28 of the aprons 14 and 16. Further, the grooves 38 and 40 can intersect one another or even extend beyond one another, although this is not desirable because grooves of excessively large size only weaken the leg 18. The grooves 38 and 40 are preferably spaced apart so that two portions 48 and 50 of the leg 18 which are formed at the upper end by the grooves 38 and 40 will be connected by a web portion 52 for maximum strength. The web portion 52 would be eliminated if the grooves 38 and 40 intersected, so that the leg portions 48 and 50 would no longer be connecting.

The grooves 38 and 40 preferably are at least as long as the aprons 14 and 16 are wide so that the leg end 42 will abut the surface 20 to improve the appearance and to add strength to the construction. If the grooves 38 and 40 are made with conventional routers, lower ends 54 and 56 of the grooves, while perpendicular to the bottom walls 44 and 46, usually will not be parallel to the lower edges of the end portions of the aprons 14 and 16, if the leg 18 either converges or diverges. If the legs diverge, as shown in FIG. 2, and the grooves are made long enough so that the ends 54 and 56 clear the end portions of the aprons 14 and 16, a slight gap will result at the

surfaces 34 and 36 of the leg, as shown in FIG. 2. This is not a serious problem, however, because the gap is not readily apparent in most cases. In extreme cases, the end portions of the aprons 14 and 16 can be beveled slightly so that they will not interfere with the ends 54 and 56 of the grooves 38 and 40 when the grooves are made just long enough to clear the edges of the aprons 14 and 16 adjacent the leg surfaces 34 and 36. If the legs converge, the grooves 38 and 40 are made long enough for the groove ends 54 and 56 to clear the edges of the aprons 14 and 16 adjacent the leg surfaces 34 and 36, with the extreme end edges of the aprons 14 and 16 then spaced slightly from the groove ends 54 and 56. This spacing is immaterial since the resulting gaps are hidden and do not lessen the strength of the construction.

The "groove angle," defined as the angle made between parallel side walls 58 and 60 of the grooves 38 and 40 taken in a plane parallel to the surface 20, must be equal to the apron angle in order to assemble the leg 18. It is also necessary that each of the "surface-apron angles" be equal to the corresponding "surface-leg groove angle." The surface-apron angle is the angle the apron 14 or 16 makes with the surface 20 in a plane perpendicular to the surface 20 and to the apron. The surface-leg groove angle is the angle the leg groove 38 or 40, when the leg 18 is in assembled relationship, makes with the surface 20 in a plane perpendicular to the surface 20 and to a side wall of the groove. When these corresponding angles are equal, and if the grooves 38 and 40 are sufficiently deep and long enough, the leg 18 can be assembled with the aprons 14 and 16 regardless of whether they converge or diverge and regardless of whether the apron angle is equal to or more or less than 90 degrees. For circular or oval aprons, the two grooves 38 and 40 are substantially 180° apart so as to be one groove for practical purposes.

As shown in FIG. 4, the sidewalls 58 and 60 of the grooves 38 and 40 converge toward the surfaces 36 and 34, respectively, of the leg 18. This does not affect assembly of the article, however, as long as the angular relationships discussed above hold true. If the legs 18 are to be disposed vertically or perpendicular to the surface 20 then the sidewalls 58 and 60 of the grooves 38 and 40 will be parallel to the surfaces 36 and 34 throughout their lengths, and if the legs converge, then the sidewalls 58 and 60 will diverge in a downward direction with respect to the surfaces 36 and 34.

While the grooves 38 and 40 are shown as being perpendicular to the surfaces 34 and 36 respectively, the grooves can be cut at any angle in the leg as long as their relationship toward one another remains the same. For example, the grooves can be at 45 degree angles to the opposed surfaces 30 and 36 or 32 and 34 rather than being perpendicular to the adjacent surfaces 34 and 36. The grooves also can be formed in round legs with equal facility.

The width of the grooves 38 and 40 can be controlled so as to provide a frictional fit with the aprons 14 and 16. Where additional means of preventing separation of the leg from the aprons and supporting member is desired, a screw hole 62 can be drilled in the leg, as shown in FIG. 1, with a screw 64 positioned in this hole to be driven against or into the end portion of the apron 14, when assembled. The screw hole and screw are at an angle to the surface 20 so as to be more accessible, but otherwise can be parallel to the surface 20, from a functional standpoint. In place of the screw, the end 42 of the leg 18 can be glued to the surface 20, for example.

Referring more particularly to FIGS. 5 and 6, a modified table 66 includes a modified supporting member or table top 68 from which aprons 70 and 72 and a leg 74 depend. The supporting member 68, in this instance, includes frame members 76 and 78 which form a flat supporting surface 80. The supporting member 68 also includes a bridging sheet 82 of thinner material includ-

ing an upper plastic lamination, as is commonly employed in the manufacture of inexpensive plastic-topped tables.

In this instance, the aprons 70 and 72 are affixed to the supporting member 68 by being fastened to the inner edges of the frame members 76 and 78 by means of nails 84 and glue, for example. The construction otherwise is the same as that of FIGS. 1-4 except that only a rear surface 86 of the butt end of the leg 74 contacts the frame members 76 and 78 while a front portion 88 of the butt end is spaced from the top sheet or plate 82. It may be noted that with this construction, the aprons 70 and 72 can be as thin as the aprons 14 and 16 of FIGS. 1-4.

From the above discussion, it will be apparent that the new construction has many advantages. By employing the shallow groove and glue or the nail and frame technique for affixing the aprons 14 and 16 to the supporting member 12, the aprons can be actually much thinner, in fact only half as thick, as conventional ones. Two of the aprons can be made from one-inch stock, for example, whereas only one can be made from such stock for conventional aprons. The extra thickness is required in conventional aprons because such aprons are screwed to their supporting member with the screws usually requiring one-half inch countersinks. This necessitates the use of aprons at least one-half inch thick and extra thickness is usually needed to prevent undue weakness resulting from the screw holes drilled therein. Where tongue-and-groove joints have been used, the extra thickness is also necessary in order to make the tongues of reasonable thickness. Hence, the groove and glue or nail and frame attachment of the aprons in accordance with the invention reduces the thickness of the aprons substantially and eliminates the eight or more screws required to fasten the aprons to the supporting member, along with the drilling operations associated therewith. The leg attachment eliminates the operations required to form the tongue-and-groove joint often used and completely eliminates the steel cross braces and bolts commonly employed.

Because the entire aprons are received in the slots, there is no problem with a side gap appearing during contraction of the aprons; further, round legs or legs with angular walls can be employed without the necessity of specially shaping the ends of the aprons to fit therewith. As another feature of the new construction, it is possible to adjust the lengths of the legs relative to the floor simply by pulling a leg slightly away from the supporting member 12 to space the butt end 42 from the surface 20. A shim can be placed in this space, if desired. A slight gap or an increased gap is then formed between the lower edge of the apron and the end of the groove but this is not noticeable in most instances. The efficient knock-down feature resulting from the construction also reduces shipping costs by a substantial amount.

Various modifications of the above described embodiment of the invention will be apparent to those skilled in the art, and it is to be understood that such modifications can be made without departing from the scope of the invention, if they are within the spirit and the tenor of the accompanying claims.

What I claim is:

1. An article of furniture of the class described comprising a supporting member having a flat surface, said surface having a pair of shallow grooves lying at a predetermined angle with respect to one another, a pair of aprons affixed in said grooves, said aprons being of uniform thickness throughout their entire lengths, said aprons forming an apron angle which is equal to the angle between said grooves, said aprons also forming predetermined surface-apron angles, a leg having two leg grooves extending from an end thereof, said leg grooves extending toward the other end of said leg a distance substantially at least as great as the width of end portions of

said aprons, said leg grooves being substantially as wide as said aprons are thick, the bottoms of said leg grooves being at least as close together as the ends of said aprons, said leg grooves forming a groove angle which is substantially equal to said apron angle, each of said leg grooves forming a surface-leg groove angle equal to the surface-apron angle of the respective apron, said end portions of said aprons being held in said grooves.

2. An article according to claim 1 wherein said groove angle and said apron angle are in the order of 90 degrees.

3. An article of furniture comprising a supporting member, a pair of aprons extending below a surface of said supporting member, each at a predetermined surface-apron angle, said aprons forming an apron angle therebetween, a leg with two grooves in an end thereof to receive end portions of said aprons, said apron end portions and at least additional portions of said aprons extending toward the opposite end being of constant thickness, said grooves forming a groove angle equal to said apron angle, each of said grooves extending into the leg a distance substantially at least as great as the width of an end portion of the respective one of said aprons, each of said grooves being substantially as wide as the respective apron is thick, said grooves supporting said aprons relative to one another and holding said leg in predetermined relationship with respect to said supporting member, and each of said grooves forming a surface-leg groove angle equal to the surface-apron angle of the respective apron.

4. An article according to claim 3 characterized by a single screw extending through a portion of said leg between said aprons and into one of said apron end portions for holding said leg in assembled relationship with said aprons.

5. An article according to claim 3 wherein said supporting member is a frame and said aprons are affixed to inner edges of said frame.

6. An article of furniture comprising a supporting member, a pair of aprons extending below a surface of said supporting member, each at a predetermined surface-apron angle, said aprons forming an apron angle therebetween, a leg with two grooves in an end thereof to receive end portions of said aprons, said end portions of said aprons and additional portions of said aprons extending beyond said leg grooves toward the opposite ends of said aprons being of constant thickness, said grooves forming a groove angle equal to said apron angle, said grooves supporting said aprons relative to one another and holding said leg in predetermined relationship with respect to said supporting member, and each of said grooves forming a surface-leg groove angle equal to the surface-apron angle of the respective apron, said apron end portions being sufficiently long and said leg grooves being sufficiently deep to enable said leg to support said article through said aprons without fasteners.

7. An article according to claim 6 and a single screw extending through a portion of said leg between said aprons and into one of said apron end portions for holding said leg in assembled relationship with said aprons.

8. An article according to claim 1 wherein said surface-apron angles are substantially 90° and said leg extends outwardly from the article.

5 9. An article of furniture comprising a supporting member having a flat lower surface, said surface having a pair of shallow grooves lying at a predetermined angle with respect to one another, a pair of aprons, an edge of each of which is affixed in one of said grooves by adhesive, the ends of said aprons being joined together at the ends of said grooves, said aprons being of uniform thickness throughout their entire lengths, said aprons forming an apron angle which is equal to the angle between said grooves, said aprons also forming equal predetermined surface-apron angles, a leg having two leg grooves extending from an end thereof, said leg grooves extending toward the other end of the leg a distance substantially at least as great as the width of end portions of said aprons to be received in said leg grooves, said leg grooves being substantially as wide as said aprons are thick, said leg grooves forming a groove angle which is substantially equal to said apron angle, said leg grooves forming surface-leg groove angles equal to the surface-apron angles, said end portions of said aprons being held in said leg grooves with the end of said leg substantially contacting the adjacent surface of said supporting member.

10. An article of furniture comprising a supporting member having a flat lower surface, said surface having a pair of shallow grooves lying at a predetermined angle with respect to one another, a pair of aprons, an edge of each of which is affixed in one of said grooves by adhesive located between a portion of the edge and the respective groove, the ends of said aprons terminating at the ends of said grooves, said aprons being of uniform thickness from one end to the other, said aprons forming an apron angle which is equal to the angle between said grooves, said aprons also forming equal predetermined surface-apron angles, a leg having two grooves extending from an end thereof, said leg grooves extending toward the other end of the leg a distance substantially at least as great as the width of end portions of said aprons to be received in said leg grooves, said leg grooves being substantially as wide as said aprons are thick, the bottoms of said leg grooves being at least as close together as the ends of said aprons, said leg grooves forming a groove angle which is substantially equal to said apron angle, said leg grooves forming surface-leg groove angles equal to the surface-apron angles, said end portions of said aprons being held in said leg grooves with the end of said leg contacting adjacent surface of said supporting member.
